ELECTRIC CLOCK

Filed May 25, 1927

INVENTOR:

Kenneth G. Williams
BY David G. Carlson
ATTORNEY.

UNITED STATES PATENT OFFICE

KENNETH G. WILLIAMS, OF ST. PAUL, MINNESOTA

ELECTRIC CLOCK

Application filed May 25, 1927. Serial No. 194,069.

My invention relates to an improved electric clock particularly adapted to be driven by an A. C. motor. The object of the invention is to provide an improved and efficient 5 electrically operated clock.

In the accompanying drawing:—

Fig. 1 is a front elevation of the works of a clock embodying my improvements.

10 Fig. 2 is a right hand edge view of Fig. 1.

Fig. 3 is a rear elevation of Fig. 1.

15 Fig. 4 is a fragmentary view, in actual size, of the upper part of a clock dial and my reset signal.

Referring to the drawing by reference numerals 10 designates a front frame plate, 11 a similar rear plate, both connected rigidly by suitable braces 12, all forming a skeletonized prismatic mechanism frame in which is mounted all the clock mechanism more generally called the "works."

13 is the hour hand arbor and 14 the minute hand arbor projecting outwardly and through a dial 15 (see Fig. 4). 16 is the main driven gear of the clock mechanism

20 fixed on arbor 14 and rotates one revolution per hour, suitable gear reduction means connected with gear 16 being all well known in the art and used to rotate arbor 13 one revolution per each 12 hours. Said gear 16 is 25 driven by a pinion 17 on shaft 18, the latter having a large gear 19 rotated by a pinion 20 to revolve one revolution per minute, said pinion 20 fixed on a shaft 21 projecting out from a transmission housing 22 mounted 30 within the lower part of the frame.

25 23 is an A. C. motor preferably of 3600 R. P. M., and its armature shaft 24 (see Fig. 1) connected to the gear reduction means within housing 22 to rotate pinion 20 at a 30 speed of 1 R. P. M.

I will now describe my releasing means for starting and stopping the clock ringing mechanism, usually at the hour and half hour.

40 24 is a disc cam on shaft 14, with two di-

ametrically opposite radial shoulders, 25 is an oscillatable cam engaging arm pivotably fixed in a shaft 26 in the front and rear plates 10—11 and above said disc cam.

The free end of said arm 25 normally engages one shoulder 24S of the cam being oscillated in a vertical plane by the movement of said cam and said movement oscillating the shaft 26 to raise another arm 27 fixed in said shaft and extending toward the right hand side and in front of plate 10. 28 is a retrieving coil spring pressing downwardly on arm 27 the latter being movable downwardly to a certain position only as shown in Figs. 1 and 2. At the extremity of arm 27 I provide a depending pivoted gate plate 29 pressed with its lower edge against the outer face of plate 10 by a coil spring 30 or like means. 31 and 32 are two parallel vertical slots in plate 10 all but the lower parts of 60 said slots being normally covered by plate 29. 42 is a pin in the central part of frame plate 10 to limit downward movement of 65 arm 27.

In Fig. 1 it will be seen that movement of 70 cam 24 causes shoulder 24S to raise arms 25 and 27 and thus plate 29 is sprung upwardly to about the dotted line position and above slot 31, the lower edge of said plate 29 passing over the front protruding end of a lever 75 33 movable vertically in slot 31 and pivoted at 34 near rear plate 11. Plate 29 is moved downwardly as from its dotted position in Fig. 1, to full line position when cam part 24S passes end lever 25, its lower edge engages the protruding end of lever 33, tilts the latter downwardly and causes meshing of certain gears at the rear of the frame and which will now be described. The pivot shaft 34 carries a yoke arm 35 which engages a recessed collar 36 on a shaft 37 journaled in plate 11 and a brace 38 (see Figs. 2 and 3). The downward movement of lever 33 causes yoke 36 to move shaft 37 forward and brings a pinion 39 into mesh with gear 19. 40 is a 80 85 90

strike control gear fixed on shaft 37 close to and rearward of pinion 39. This control gear has the usual perimetral shallow teeth 40A and deep notches 40B (Figs. 3 and 5) which control the striking means to sound the hour or half hour. 41 is a flat spring fixed to the upper and inner part of rear plate 11, its lower end normally pressing shaft 37 and its gears rearwardly in free position and lever 33 normally in upper position as shown in Fig. 2.

The above described operation throwing pinion 39 into mesh with the constantly running drive gear 19 sets up the striking mechanism of my clock. It is obvious that pinion 39 immediately starts to rotate when engaged with gear 19 and then gear 40 rotates as indicated by arrow 43, in Fig. 3, said gear having the regulation shallow and deep notches arranged successively for striking the hours and half hours, and is hereinafter referred to as the striking gear. 44 is a downwardly directed angular flat tooth (see Fig. 3) on the lower side of an angular vertically movable lever 45 the upper end of which is pivoted on a horizontal shaft 46 in the upper part of the frame, 47 is a U-shaped yoke fixed on and depending from shaft 46, the lower terminus of said yoke being pivotally connected at 48 to a reach rod 49 extending toward the right side of the frame (see Fig. 1) the latter end of said rod connected at 50 to a horizontal arm 51 of a vertically disposed, horizontally oscillatable spring housing 52 mounted on the inner side of plate 11. Said housing has another arm 53 of L-shaped extending downwardly and thence horizontally toward the right side of the frame and with its extremity pivotally engaging a kick-off bar 54 arranged below and approximately in parallel relation to lever 33. The forward end of said bar 54 is continuously in the slot 32 and is normally pressed upwardly in said slot and outwardly by means of spring arms 45 of a coil spring 55 (see Fig. 2). It will now be understood that when shoulder or tooth 24S of disc 24 causes levers 25-27 to raise plate 29 the subsequent downward movement of plate 29 causes it to engage the end of lever 33 as described throwing gear 39 into mesh and the striking gear immediately moves and the finger rides the shallow notches thereof, one by one, making small vibrations or oscillations of arm 45, yoke 47, moving bar 49, 55 which oscillates spring housing 52. The latter oscillates lever 53 which makes short oscillating movements of kick-off bar 54. The free end of said latter bar at this time, is close to the plate 29 and inwardly thereof. However when finger 44 of arm 45 drops into a deep notch 40B of the striking gear it is obvious that bar 54 is given a comparatively long stroke and its free end will kick-out against plate 29 and release it from engagement with lever 33. The latter of course is

instantly sprung upwardly by spring 41 pressing gear shaft 37 rearwardly, disengaging gear 39 and striking ceases.

78 in Fig. 1 is an upright lever with its lower end normally held against the magnetic field of motor 23, the upper end of said lever pivoted at 79 in the upper part of the frame, and having a lever arm 78A (Fig. 4) forward of and above the main frame extending toward the dial 15 of the clock. On the free end of said lever 78A is fixed an arched sign 80 with the word Reset on it, said sign normally above the dial but will swing downwardly in front of the dial when the current is accidentally or otherwise shut off and arm 78 automatically drops to a vertical position. It will then be clearly visible that the clock has stopped when the sign has dropped down over the dial. Any person observing the signal can start the clock by simply pressing upwardly on a trigger arm 78B fixed on the rear end of the pivoted part of lever 78. This latter action restores the lever 78 to contact with the magnetic field of the motor. It is obvious of course that the person who thus starts the clock again must first reset the hour and minute hands to indicate the correct time.

I claim:

In an electric clock with a minute hand arbor an hour hand arbor concentric thereof and suitable gears including a striking gear mounted on a shaft and driven by a motor to rotate said arbors at a predetermined speed relative to the motor speed, said striking gear having a predetermined number of shallow and deep notches, an oscillatable lever normally engaging said notches; time signal means and releasing means therefor comprising a disc fixed on the minute hand arbor and having cam teeth, a two armed releasing member and a spring pressing same downwardly, said member pivoted above said cam and one arm thereof arranged in the path of said cam teeth to be raised thereby and to raise the other and longer arm of said releasing member, said latter arm movable in a vertical plane and upwardly and carrying a hinged plate at its free end and spring pressed against the front frame of the clock, said frame provided with a pair of vertical parallel slots and over which said plate is movable, a primary release lever pivotally mounted transversely to the face of the clock and normally spring pressed upwardly and its free end normally protruding forwardly of one of said slots, a pinion fixed on the shaft of said striking gear, operative connection between said primary release lever and said striking gear shaft to move the latter forwardly and mesh said pinion with a gear of the clock mechanism to cause rotation of the striking gear, said hinged plate of the two armed release device adapted to be pressed downwardly immediately after a cam of the disc has passed its short arm and engage the

protruding end of said primary release lever and push the latter down to cause said striking gear to rotate, and a kick-off device comprising a secondary release lever arranged parallel to the first described release lever, the free end of said kick-off lever normally in the other of said two parallel slots and arranged to be pushed against said spring pressed plate to swing the latter out and to disengage it from the primary release lever, when the oscillatable lever engages one of said deep notches.

In testimony whereof I affix my signature.
KENNETH G. WILLIAMS.
